UNITED STATES PATENT OFFICE.

KARL GUSTAF ANDERSSON, OF SKOGSFORS, REFTELED, SWEDEN, ASSIGNOR OF ONE-
THIRD TO JOHAN AUGUST PETERSON, OF REFTELED, SWEDEN.

DIESTOCK.

1,331,973.

Specification of Letters Patent. Patented Feb. 24, 1920.

Application filed September 28, 1918. Serial No. 256,110.

To all whom it may concern:

Be it known that I, KARL GUSTAF ANDERSSON, a subject of the King of Sweden, residing at Skogsfors, Reftele, in the Kingdom of Sweden, have invented a new and useful Improvement in Diestocks, of which the following is a specification.

The present invention relates to a die-stock of the type in which the dies may be moved into and out of engagement with the work by means of a rotatable ring or sleeve connected with the dies, which ring or sleeve may be turned by means of a mechanism attached to one or both of the handles of the die-stock.

The invention is broadly characterized by this that the said mechanism is located within one or both of the tubular handles by means of which the die-stock is turned, and is so connected with the ring that the ring may be turned in one and the other direction by means of the said mechanism so that the dies may be moved into as well as out of engagement with the work. By this arrangement the mechanism is very effectively protected against being damaged or spoiled, and the essential advantage is also attained that the tool may be made devoid of springs, in contradistinction to die-stocks of this type as heretofore known, in which the ring or the sleeve has been connected with one or several springs for being turned in the direction corresponding to the movement of the dies out of engagement with the work.

A further important feature of the invention consists in the rotatable ring or sleeve being divided into two concentrically arranged members rotatable and adjustable relatively to one another, one member being connected with the handle mechanism and the other member being connected with the dies. By rotating and adjusting the latter member relatively to the first mentioned member the mutual position of the dies in working position and in open position may be changed, consequently, when the dies have become worn and resharpened they may be readjusted to compensate for their decreased dimensions so as to suit the desired diameter of the screw, by adjustment of the member or part of the ring connected with the dies.

The invention also comprises improved means for connecting the dies with the said

member or part of the ring, as well as special means for rotating and locking the ring or the sleeve, which means will be further described here below with reference to the accompanying drawings, which illustrate an embodiment of the invention.

In the drawings Figure 1 shows a plan view of the die-stock with the cover removed and with the dies in working position. Fig. 2 shows a side view of the die-stock, one of the handles and part of the mechanism being shown in section. Fig. 3 shows a view similar to Fig. 1, of the die-stock with the dies in open position. Fig. 4 shows a plan view of the member or part of the rotatable ring or sleeve connected with and actuating the dies. Fig. 5 shows a plan view of the member or part of the ring or sleeve connected with the handle mechanism. Fig. 6 shows a side view partly in section of one of the dies and the means for connecting the dies with the ring, as well as the means for locking the two members of the ring together.

The frame of the die-stock consists of the bottom 1 with the central hub 2 serving for guiding the dies, and the lateral portions 3 into which the handles 4 of the die-stock are screwed. The hub 2 is surrounded by and forms a guide for a rotatable ring which consists of an upper part or member 5, Fig. 4, and a lower part or member 6, Fig. 5. The lower member 6 is turned down at 7 to form a bearing surface for a flange 8 on the upper member 5. The lower member 6 is cut open at 9, where it is provided with a conical and threaded hole 10 in which a conical screw 11 is screwed from the bottom of said member 6. By screwing the screw 11 into the hole 10 the lower member 6 is widened so that the upper member 5 is securely clamped to the same. When the screw 11 is screwed out of said hole 10 the member 6 again contracts so that the member 5 may be rotated and adjusted on the member 6 for adjustment of the dies when worn and resharpened.

The dies 12 which are placed and guided into radial grooves in the hub 2, are connected with the upper member 5 by means of hooks 13, Fig. 6, which are introduced into openings in the dies 12 and engage eccentrically arranged grooves 14 in the upper member 5. This means of connecting the dies 12 and the member 5 is simple and in-

expensive to manufacture, it being only necessary to provide the dies 12 with holes for the hooks 13, which are easily manufactured and which may readily be replaced when required.

The mechanism for rotating the ring is located in one of the handles of the die-stock. In the tubular handle 4 a piston 15 is movable near the portion 3 of the die-stock frame, said piston being connected by means of the rod 16 with the lever 18 which is pivoted on the stud 17. The piston 15 is provided with an oblique surface 19 at its inner end. When the piston 15 is moved inward 10 toward the center of the die-stock this oblique surface engages one edge of a notch 20, Fig. 5, in the lower ring member 6. This member 6 is provided with another notch 21 engaged by a hook 22 on a rod 23 provided at its other end with a head 24 movable in a slot 25 in the piston 15. These members operate in the following manner:

When the lever 18 is turned out from the handle 4 the piston 15 occupies its retracted 25 position shown in Fig. 3 and the dies 12 are in open position. When the dies 12 are to be moved into working position the lever 18 is turned into the handle 4 thereby moving the piston 15 inward by means of the rod 16. 30 Owing to this movement of the piston 15 the rod 23 is also moved, said rod causing the initial rotation of the two ring members 5 and 6. At the further movement of the piston 15 and of the ring members the oblique 35 surface 19 on the piston engages one edge of the notch 20 in the ring member 6, and owing to this engagement the further inward movement of the piston 15 will effect the further rotation of the ring members 5 and 6, until 40 the piston 15 arrives in the position shown in Fig. 1 in which it projects into the notch 20 and locks the ring members 5 and 6 and the dies 12 in the working position. The piston 15 arrives into this position by the turning 45 of the lever 18 into alignment with the handle 4. When the dies 12 are to be retracted the lever 18 is turned out from the handle 4 thereby retracting the piston 15. When the piston 15 is retracted so far that 50 the oblique surface 19 releases the edge of the notch 20, the piston exerts a pull on the rod 23 which effects the further backward turning of the ring members 5 and 6 until the dies 12 arrive into idle positions.

It is obvious that various changes and modifications may be made in the detailed construction herein illustrated and described, and the right is therefore reserved to make such changes and modifications as fall within 55 the scope of the appended claims.

I claim:

1. In a die-stock, the combination of a frame, dies movable in said frame, a ring rotatable in said frame and connected with 65 said dies, a tubular handle secured to said

frame, and means located within said handle for rotating said ring in both directions.

2. In a die-stock, the combination of a frame, dies movable in said frame, a ring rotatable in said frame and provided with a 70 notch, means connecting said dies to said ring, a tubular handle secured to said frame, a piston movable in said handle and provided with an oblique surface adapted to engage one edge of said slot in said ring, and means within said handle for rotating said ring in both directions and for moving said piston toward and away from said ring. 75

3. In a die-stock, the combination of a frame, dies movable in said frame, a ring rotatable in said frame and provided with a notch, means connecting said dies to said ring, a tubular handle secured to said frame, a piston movable in said handle and provided with an oblique surface adapted to 80 engage one edge of said slot in said ring, a rod pivotally connected at one end to said ring and at its other end to said piston, and means within said handle for moving said piston toward and away from said ring. 90

4. In a die-stock, the combination of a frame, dies movable in said frame, a ring rotatable in said frame, said ring comprising two members rotatable and adjustable relatively to one another, means connecting 95 said dies to one of said ring members, a tubular handle secured to said frame, and means within said handle for rotating the second ring member in both directions.

5. In a die-stock, the combination of a 100 frame, dies movable in said frame, a ring rotatable in said frame, said ring comprising two members rotatable and adjustable relatively to one another, one of said ring members being provided with eccentric 105 grooves and the second ring member being provided with a notch, means for securing said ring members to one another in adjusted position, means connecting said dies to the firstnamed ring member and co-operating with said eccentric grooves, a tubular handle secured to said frame, a piston movable in said handle and provided with an oblique surface adapted to engage one edge of said slot in said second ring member, a 110 rod pivotally connected at one end to said second ring member and at its other end to said piston, and means within said handle for moving said piston toward and away from said ring. 115

6. In a die-stock, the combination of a frame, dies movable in said frame, a ring member rotatable in said frame and provided with eccentric grooves, means connecting said dies to said ring member and co-operating with said eccentric grooves, a substantially cylindrical flange on said ring member, a slotted second ring member rotatable in said frame and provided with a notch, a substantially cylindrical portion 120 125 130

on said second ring member fitting into said cylindrical flange, means comprising a conical screw threaded into a correspondingly threaded hole at the slot in said second ring member for extending said second ring member and for securing said two ring members to one another in adjusted position, a tubular handle secured to said frame, a piston movable in said handle and provided with an oblique surface adapted to engage one edge of said slot in said second ring member, a rod pivotally connected at one end to said second ring member and at its other end to said piston, and means within said handle for moving said piston toward and away from said ring members.

7. In a die-stock, the combination of a frame, dies movable in said frame and provided with holes, a ring member rotatable in said frame and provided with eccentric grooves, hooks introduced into said holes in said dies and into said eccentric grooves

in said ring member, a substantially cylindrical flange on said ring member, a slotted second ring member rotatable in said frame 25 and provided with a notch, a substantially cylindrical portion on said second ring member fitting into said cylindrical flange, means comprising a conical screw threaded into a correspondingly threaded hole at the slot in said second ring member for extending said second ring member and for securing said two ring members to one another in adjusted position, a tubular handle secured to said frame, a piston movable in 30 said handle and provided with an oblique surface adapted to engage one edge of said slot in said second ring member, a rod pivotally connected at one end to said second ring member and at its other end to said piston, and means within said handle for moving said piston toward and away from 35 said ring members.

KARL GUSTAF ANDERSSON.
